[57] CLAIM

The ornamental design for a bridge for a guitar, as shown and described.

DESCRIPTION

FIG. 1 is a perspective view of a bridge for a guitar showing my new design.

FIG. 2 is a front view thereof;

FIG. 3 is a back view thereof;

FIG. 4 is a top view thereof;

FIG. 5 is a bottom view thereof;

FIG. 6 is a left side view thereof; and

FIG. 7 is a right side view thereof; and,

FIG. 8 is a reduced top view of my new bridge for a guitar installed on a guitar. The broken lines shown are for illustrative purposes only and form no part of the claimed design.
